COMBINED SHIRT AND SHORTS

Blanche F. Hall, Kansas City, Mo.

Application October 4, 1933, Serial No. 692,184

6 Claims. (CL 2—115)

The invention relates to a combined shirt and shorts for boys.

The object of the present invention is to improve the construction of boys shirts and to provide a simple, practical and comparatively inexpensive garment equipped with means for preventing a shirt from working up out of the trousers when the latter are supported with or without a belt and worn without suspenders.

10 A further object of the invention is to provide a shirt having two shorts-forming members permanently connected at one end to the back portion of a shirt and longitudinally tapered and adjustably and detachably secured at their other end to the front portion of the shirt to form shorts with leg openings at the sides thereof and crossed intermediate of the ends to provide a closed crotch.

It is also an object of the invention to provide 20 shorts-forming members adapted to securely hold the shirt down and at the same time provide ample fullness of the garment at the leg openings.

Another object of the invention is to provide 25 crossed shorts-forming members adapted to be readily spread apart when required and capable of normally remaining in closed overlapped relation to provide practically a completely closed garment between the outer side edges of the shorts.

30 With these and other objects in view, the invention consists in the construction and novel combination and arrangement of parts herein-after fully described, illustrated in the accompanying drawing and pointed out in the claims 35 hereto appended, it being understood that various changes in the form, proportion and minor details of construction, within the scope of the claims, may be resorted to without departing from the spirit or sacrificing any of the advantages of the invention.

In the drawing:—

Figure 1 is a front elevation of a shirt constructed in accordance with this invention, the 40 shorts-forming members being detachably secured together at their front or free ends and adjustably and detachably connected to the front portion of the shirt.

Fig. 2 is a similar view of the lower portion 45 of the shirt, the shorts-forming members being detached from the front of the shirt.

Fig. 3 is a similar view with the front portion of the shirt broken away to show the full length of the shorts-forming members.

50 Fig. 4 is a rear elevation of the lower portion

of the shirt, the parts being arranged as illustrated in Fig. 2.

In the accompanying drawing in which is illustrated the preferred embodiment of the invention, 1 designates a shirt composed of front and rear portions 2 and 3 of the usual construction, and while the shirt is designed particularly for the use of boys, the garment may, of course, be made of any desired size to fit either boys or adults. The shirt is provided with two shorts-forming members 4 and 5 tapered longitudinally and permanently connected at their larger ends to the back portion 3 of the shirt at the waist line by being stitched to the same. The members 4 and 5 which are relatively wide at their inner larger ends are overlapped and are crossed adjacent their free smaller ends and are preferably detachably connected at such point of crossing by means of a button 6 carried by the member 5 and a buttonhole 7 formed in the member 4.

15 The overlapping and the crossing of the smaller ends of the members form a closed crotch which is maintained securely closed when the garment is in use. The free ends 8 and 9 of the members 4 and 5 are provided with buttonholes 20 10 and 11 which are adapted to engage buttons 12 and 13 arranged in pairs, as clearly illustrated in Figs. 1 and 2 of the drawing. Two sets or pairs of buttons 12 and 13 are preferably provided but any number of sets may, of course, be 25 employed, and any other suitable means may be provided for detachably securing the free ends of the members to the front portion of the shirt.

30 The buttons 12 and 13 are located centrally of the front portion of the shirt adjacent the waist line and they permit the size of the shorts formed by the said members to be varied. The smaller ends of the members are reinforced to provide substantially triangular tab-like portions 14 and 14^a and each of the members consists of two 35 pieces 15 and 16 having their adjacent edges 17 and 18 cut on a bias and stitched together. The outer edge 19 of the piece 15 is straight and the outer edge 20 of the piece 16 is curved 40 to provide the desired width of the shorts at 45 the back. Each outer piece 16 of the members 4 and 5 is provided at its outer edge with an inwardly tapered transversely disposed gusset 21 extending inwardly from the outer edge of the section 16 and tapered inwardly and adapted to 50 provide a fullness of the garment at the leg openings formed by looping the members 4 and 5, as clearly illustrated in Fig. 1 of the drawing, to 55 provide the shorts.

The shorts-forming members are adapted to 55

hold the shirt down and there will be no liability of the tail of the shirt working out of the trousers and this difficulty with boys' shirts will be entirely eliminated. The front portion of the shirt is provided with extensions 22 which cooperate with the said members in the formation of the shorts, as clearly shown in Fig. 1 of the drawing. The garment consisting of the combined shirt and shorts is easily and quickly applied to a person and readily removed. The legs of the wearer extend through the side openings 23 formed by the members 4 and 5 and the extensions 22 of the front portion 3 of the shirt, as clearly shown in Fig. 1 of the drawing.

15 What is claimed is:

1. In a garment of the class described, the combination with the front and rear portions of a shirt, of two shorts-forming members overlapped and crossed and permanently connected 20 at one end to one of said portions of the shirt and detachably connected at the other end to the other of said portions of the shirt, each shorts-forming member being separate from the other to the point where they are permanently connected to the shirt and being sufficiently wide to overlap the major portion of their width to form a closed crotch and adapted to hold the front and back portions of the shirt down in proper position.
- 30 2. In a garment of the class described, the combination with the front and rear portions of a shirt, of two shorts-forming members overlapped and crossed and permanently connected to the rear portion of the shirt adjacent the 35 waist-line and detachably secured at their free ends to the front portion of the shirt, each shorts-forming member being separate from the other to the point where they are permanently secured to the shirt and being sufficiently wide to overlap the major portion of their width to form a closed crotch and adapted to hold the front and back portions of the shirt down in proper position.
- 40 3. In a garment of the class described, the 45 combination with the front and rear portions of a shirt, of two longitudinally tapered shorts-forming members extending at their wide ends from the rear portion of the shirt and overlapped and crossed, each shorts-forming member being separate from the other to the rear portion of the shirt where they are connected with the same and being sufficiently wide to overlap the major portion of their width to form a closed crotch and each of said members being composed of two longitudinal pieces arranged side by side and having their adjacent edges cut on a bias and secured together, the marginal

edge of the member at the side of the garment being curved and the other marginal edge of the member being straight, and means for detachably securing the free ends of the members to the front portion of the shirt.

4. In a garment of the class described, the combination with the front and rear portions of a shirt, of two longitudinally tapered shorts-forming members permanently connected at their wide ends to the rear portion of the shirt and overlapped and crossed, each shorts-forming member being separate from the other to a point where they are permanently connected to the back of the shirt, and being sufficiently wide to overlap the major portion of their width to form a closed crotch and each member having a curved marginal edge located at the side of a garment, the other marginal edge of the member being straight, inwardly tapered gussets secured in the members intermediate the ends thereof and extending transversely of the same from the curved marginal edges thereof to increase the fullness of the shorts, and means for detachably securing the free ends of the members to the front portion of the shirt.

5. In a garment of the class described, the combination with the front and rear portions of a shirt, of two shorts-forming members overlapped and crossed and extending from the rear portion of the shirt, each shorts-forming member being separate from the other to the point where they are permanently connected to the rear portion of the shirt and being sufficiently wide to overlap the major portion of their width to form a closed crotch, the free ends of the said members having triangular shaped reenforcing tabs provided with means for detachably connecting the free ends of the members to the front of the shirt.

6. In a garment of the class described, the combination with the front and rear portions of a shirt, of two shorts-forming members overlapped and crossed and permanently connected at one end to the rear portion of the shirt, each shorts-forming member being separate from the other to the point where they are permanently connected to the shirt and being sufficiently wide to overlap the major portion of their width to form a closed crotch and adapted to hold the front and back portions of the shirt thereon in proper position, the free ends of the members being provided with triangular shaped reenforcing tabs, means for detachably securing the tabs together, and spaced means for detachably securing the tabs to the front portion of the shirt.
